UNITED STATES PATENT OFFICE.

ROBERT M. NASH, OF OKLAHOMA, OKLAHOMA.

PAGE FOR BOOKKEEPING.

1,368,046.

Specification of Letters Patent.

Patented Feb. 8, 1921.

Application filed February 25, 1918. Serial No. 219,050.

To all whom it may concern:

Be it known that I, ROBERT M. NASH, a citizen of the United States, and a resident of the city, county, and State of Oklahoma, 5 have invented new and useful Improvements in Pages for Bookkeeping, of which the following is a specification.

This invention has reference to a page or sheet, suitably provided and arranged for 10 the purpose of providing a simple and an efficient and inexpensive method of accounting and book-keeping, especially for those who are laymen in the art of book-keeping, so that they may keep proper accounts of 15 receipts and disbursements, obtaining thereby the proper result, so as to be able to fully meet the requirements of the Federal income tax legislation, now in force.

An object of the invention is to simplify 20 book-keeping, especially for those not specially familiar with such methods.

Another object of said invention is to combine the elements of a cash-book, journal and ledger.

25 A further object of said invention is to provide for the accurate keeping of account of receipts and disbursements of individuals, business men, partnerships, corporations, associations, classes, and all other namable enterprises.

Still another object of the invention is to be found in finding the profits and loss in business, and independent of personal accountings.

35 Other objects of said invention will appear from a further and more complete reading of the following specification.

In the drawings, Figures 1, 2, 3 and 4 are fragmentary views which together show an 40 entire page in the book.

In Fig. 1, of the drawings, *e* represents a top spacing reaching across the entire page, and at equidistantly arranged places, numerals from 1 to such number as may be required are placed, in the present instance the high number is 20.

45 Beneath this ruling *e* is another similar ruling forming a heading *f*, in which at the beginning of the page the term "Schedule" is placed, and under that term or alongside of it, and under each numeral in section *e* is placed the sign, such as "A."

A "schedule" block *g* is ruled beneath the schedule line, and thereunder are as 55 many more of such schedule blocks, as may

be necessary, for instance, as shown by *h*, *i*, *j*. Laterally of these blocks *g*, *h*, *i*, and *j*, to the left is an elongated instruction indicia receiving block *k*, and under these blocks appear the date lines and columns *l*, and item 60 and name lines and columns *m* and *n*.

Between these blocks and the columns *l*, *m* and *n*, is a division column *o*.

By reference to block *k*, which may be called the instruction block, such words or 65 instructions may appear as may best suit the needs of the book, and the purposes for which it will be used, for instance, in the present case the following may appear: "Select the schedule A, B, C, or D which 70 applies to the conditions of your business, then cross out or disregard the other schedules."

In block *g* under schedule "A" the user of the book will find these words: "For individual and partnership concerns who handle goods and merchandise," or some other such title as may be expedient. 75

In block A under number 1 appears the legend "From sale of goods or merchandise," 80 the same being designated by letter of reference *p*. This block *p* is laterally to the right of block *g* and from it blocks extend as long as numbers in section *e* appear, and these blocks all under schedule "A" as seen 85 in section *f* are lettered *q*, *r*, *s*, *t*, *u*, *v*, *w*, *x*, *y*, *z*, *a*—*a*, *b*—*b*, *c*—*c*, *d*—*d*, *e*—*e*, *f*—*f*, *g*—*g*, *h*—*h*, and *i*—*i* and running in rotation as per these letters of reference, the following informations appear: For instance at *s* under 90 column 4 appears "From rent of ground or business property" (those under numerals 5, 6 and 7, in this schedule are purposely left blank for optional filling, for special cases) under 11 appears "Paid for wages, labor and 95 salaries," thus so far as schedule A is concerned, and the receipt side of the book is concerned, all classifications of any system of accounts may be provided for to care for the business or classification of that schedule. 100

In order to save a great deal of repetition of description, it may now be explained that beneath these schedule blocks are the usual dollar and cents columns, ruled laterally to correspond with the rulings of the columns *n* and *m*, in which adjacent date in column 1 105 the name or names of parties with whom transactions are had and the item of transaction is placed, while the result of that transaction is placed in such dollar and cent 110

column generally indicated by j , j , as may be seen from the drawings. When the page is filled, the same may be totaled under column 8 as seen in the drawings.

5 Referring back now to block k , in which schedule B is located, we find "For contractors, machinists, blacksmiths, and special lines of mechanics and manufactures, etc." Laterally of this, in block number 1 for example there appears the following: "From work, material, product and so forth"; "Interest on accounts, notes, mortgages and so forth"; those under 5, 6 are blank for optional purposes, then in block 7 "From money borrowed"; in block 9 "Paid for raw materials and supplies"; in block 12 "Paid for light, fuel, power, etc"; in block 14 "Paid for ordinary repairs and incidental expenses"; in block 17 "Loss from fire, theft and casualty, not covered by insurance"; under 19 "Other miscellaneous expenditures."

In block i , the following is inscribed under schedule C: "For speculators, attorneys, agents, physicians, retired capitalists, salesmen, ministers, and all professional occupations." Laterally of this classification, the sub-classifications run as follows: for instance; "Rent in cash crops or its equivalent"; "From sale of personal property or real estate"; block 7 under "C" is left blank for optional purposes, under block 8 comes "The total received from all sources"; under block 10 appears "Paid for furniture, instruments, library and equipment"; under block 13 appears "Cost of value of real or personal property sold"; under block 15 appears "Principal and interest paid on debts or borrowed money"; under 18 appears "Donations for religious, charitable and educational purposes"; under block 20 appears "Amount drawn for personal use."

In classification j "Farmers, stock-raisers, dairymen, dealers in poultry, eggs, butter, milk and cream, and other farm products" is the preferable title, and alongside of this classification in the sections under "D" corresponding to the character "D" for the classification named, appear in rotation 50 "From compensation for services"; "From sale of garden truck, poultry, eggs, butter, and milk"; under column 12 appears "Paid for light, fuel, power etc."; under column 16 appears "Feed and forage bought for live 55 stock and poultry"; while under column 19 appears "Amount drawn for personal use."

Thus we have the ledger, journal and cash book classified in schedules, divided into headings commensurate to the necessities of 60 businesses under them.

Now, for instance, on August 1, in date column 1, "Farmer's elevator" in column n , took wheat which is recorded in column m , for which they paid \$400.00 which is set 65 down in sub-section 3 which could be classi-

fied under "D" in said numbered section. The total from all sources column would show four hundred dollars in the absence of any other credit from that concern.

Thus there is now completed a page, receipts and disbursements, each divided into such classifications as are or may be necessary to carry forth any sort of business or enterprise. By selecting any heading in any subdivision and going to the date column 1, name column n and item column m the amount of any transaction may be placed in the dollar and cent column corresponding to the sub-classification and totaled both for receipts and disbursements.

In connection with the arrangement shown in Figs. 1 to 4 inclusive of the drawings, it may be observed that the vertical amount column 8 represents a column for receiving the receipts from all sources totaled from the entire receipt side of the ledger. This has been indicated on Fig. 2 of the drawings wherein the legend "Total receipts from all sources" appears in block 8C, said legend being representative of the legends appearing in other blocks under column 8. The receipt side of the ledger therefore, embraces all of the matter contained in Fig. 1 and all of the matter of Fig. 2 up to and including column 8, while the disbursement side represents all of the matter beginning with the column 9 in Fig. 2 and also the arrangement shown in Figs. 3 and 4, which when read together in connection with the right hand side of Fig. 2 completely dis- close the disbursement side of the ledger.

By way of reviewing the distinctive features of the invention it may be observed from the foregoing description that the present ledger sheet is divided into two main sections, namely, a receipt section at the left hand side of the sheet and a disbursement section immediately adjoining to the right. These receipt and disbursement sections each have a plurality of vertical amount columns 1 to 20 inclusive ruled thereon, and a plurality of schedule rows A, B, C and D, arranged transversely at the top of said sections, whereby the blocks formed by intersection of the rows with the vertical columns form a plurality of squares or sub-divisions for receiving indicia pertinent to the main instructions contained in the blocks g , h , i and j , at the head of each row. Beneath the main schedule blocks g , h , i and j , there is arranged an item column which is divided to receive individual names of persons and articles of trade, while to the left of this column there is provided a vertical date column 1, whose upper portion provides a general instruction receiving block which gives the key to the entire sheet.

It will now be seen that a system has been created that provides a complete method of bookkeeping for those especially who are not

familiar with the methods of book-keeping, and yet, who, under the Federal tax law may be required to render an account for taxation.

By observing the schedules "A," "B," "C" and "D," and then observing the sub-classifications and especially those numerically arranged, every possible business, or enterprise, or other engagement may be found, even by placing one of an individual choosing in the sub-sections, purposely left blank for that purpose, and then in rotation name the date in the date column 1, name the person or firm in the title column n and the item in the column m and then run to the dollar and cents column corresponding to the sub-classification, selected and make the entry.

These entries are totaled at the end of each receipt page and disbursement page, and the results can be easily compiled.

Having thus described this invention, I claim:

1. A bookkeeping sheet divided into opposite receipt and disbursement sections, each section being divided into a plurality of vertical columns, a plurality of transverse lines at the top of the sheet intersecting the said lines forming the vertical columns to provide spaces for receiving main and sub-classification indicia, other transverse lines at the lower part of the sheet spaced relatively close together to divide the vertical columns into spaces adapted to receive individual amounts, a date column formed at the marginal edge of the receipt section, and the upper portion of said date column being unruled to receive suitable instruction indicia, a relatively wide column between the date column and the said vertical columns to provide at the upper portion of the receipt section a plurality of blocks to receive appropriate main schedule indicia while the lower portion of said column is formed with a plurality of spaces for receiving the names of the individual amounts

placed in said individual amount receiving spaces.

2. A bookkeeping sheet comprising receipt and disbursement sections each having a plurality of vertical columns ruled thereon, a plurality of transverse lines forming appropriately designated rows arranged transversely at the top of said sections, and each row containing a schedule indicia receiving space and also subdivisions adapted to receive indicia explanatory of the appropriate schedule arranged at the beginning of the row, an appropriately defined space common to all of said rows and adapted to receive the instructions for using said rows, a column beneath the aforesaid space and adapted to receive dates, and a column adjacent said last mentioned column and located beneath the said schedule receiving space.

3. A bookkeeping sheet divided into receipt and disbursement sections each having a plurality of vertical columns, a plurality of transverse lines at the top of said sections forming rows having subdivisions, the initial ones of which latter are adapted to receive appropriate printed matter constituting a main schedule while the remainder receive sub-title indications relating to the main schedule, a vertical column in the receipt section for receiving dates, and a plurality of relatively closely spaced transverse lines extending across both sections and intersecting the said vertical columns to provide spaces for receiving appropriate individual items and amounts falling under the classification indicated at the head of the column.

In testimony whereof I have hereunto signed my name, in the city, county and State of Oklahoma, this 18th day of February, in the year of our Lord, nineteen hundred and eighteen.

ROBERT M. NASH.
